UNITED STATES PATENT OFFICE.

HARRY J. BARNHART, OF MARION, OHIO, ASSIGNEE TO THE OSGOOD COMPANY, OF MARION, OHIO, A CORPORATION.

EXCAVATING-MACHINE.

1,301,803.

Specification of Letters Patent. Patented April 29, 1919.

Application filed February 7, 1917. Serial No. 147,046.

To all whom it may concern:

Be it known that I, HARRY J. BARNHART, a citizen of the United States, residing at Marion, in the county of Marion and State of Ohio, have invented certain new and useful Improvements in Excavating-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

In that class of excavating machinery known as "revolving shovels," a stout truck carries the house or body of the machine which is so mounted upon the truck as to permit the horizontal rotation of the body.

At one end of the body of the machine is carried a boom suitably braced and supported and which swings horizontally by means of the rotation of the body to the right or left. The boom carries a dipper-arm having mounted at its forward extremity a dipper or shovel, there being devices for projecting and retracting the dipper-arm and for raising and lowering the outer end of the arm with the dipper. In machines of this class, as heretofore usually constructed, the horizontal rotation of the body of the machine and the boom, and the raising and lowering of the dipper or shovel, have, respectively, been accomplished by

means of separate and independent engines mounted upon the body of the machine, and suitably connected or geared to the parts to be actuated, while the thrust and retraction of the dipper-arm has been effected by means of an engine located on the boom or crane.

My invention relates to machines of the class here indicated, and its object is to dispense with the separate and independent engines or motors for driving the mechanisms referred to, and to furnish a construction by which the boom, the dipper-arm actuating mechanism, and the devices for raising and lowering the dipper may conveniently be and at will be independently or simultaneously operated by a single engine or motor moving in but one direction. My invention also relates to certain details of construction hereinafter described and pointed out in the claims.

I attain the objects here indicated by means of the devices, construction and arrangement of parts hereinafter described, and shown and illustrated in the accompanying drawings, in which—

69

Figure 1 is a side-elevation of my machine, the side of the house of the machine being removed to disclose, in part, the arrangement of gears hereinafter referred to; Fig. 2, a top-plan-view of the same with the house removed; Fig. 3, a top-plan sectional view of the devices for pivotally supporting the heel of the boom and the gears for projecting and retracting the dipper-arm, and Fig. 4, an elevation, partly in central vertical section, of a preferred form of clutch-mechanism hereinafter referred to.

Like reference numerals and letters indicate like parts throughout the drawings.

In the drawings, 1 is a stout four-wheeled truck adapted to be driven by the engine of the machine through a train of gears intermediate the engine and the gears 2—3. This gearing is of the usual or any preferred form and, constituting no part of the present invention, needs not be here further described. The truck may also have a steering mechanism operated through the sprocket-wheel 4 which may be suitably connected with the engine of the machine. 75 This steering mechanism also, since it constitutes no part of the present invention, needs not be more specifically explained. Upon the top of the truck is fixed a circular rack 5 from the center of which springs a column 6 which forms a pivotal center upon which the body of the machine swings horizontally. The top of the rack 5 forms a track for wheels or rollers 7 journaled on the bottom of the frame of the body and 80 which support the body of the machine in its travel about the center 6.

The platform or deck 8 of the machine carries at its forward end the boom 9 of the machine and near its rear end the engine or motor which may be of any preferred type and which in the present instance, for illustration, is a four-cylinder gasoline engine 10. The boom 9 is adjustable vertically but transversely is rigid upon the body of the machine and carries the dipper-arm 11 which, in the usual manner, is provided at its forward extremity with the dipper or shovel 12 of the usual or any preferred construction.

110

To operate the shovel 12 three principal instrumentalities are requisite, viz., means for projecting and pressing the teeth or cutting edge of the dipper into the earth to be excavated and for retracting the dipper and dipper-arm; means for hoisting the dipper to the desired height, and means for swinging the dipper to the right or left to the point where its contents are to be discharged.

Referring first to the gears for swinging the body of the machine, together with the boom, the dipper handle and the dipper, which gears, in the present construction, lie nearest to the engine: Upon the shaft of the engine 10 is a gear-wheel 13 in mesh with a gear-wheel 14 upon one end of a shaft A which carries at its other end a pinion 15. The shaft A together with the shafts geared to and driven by the shaft A are journaled upon the side-members of a stout cast frame B mounted upon and secured to the deck or platform 8. The pinion 15 is in mesh with gear-wheel 16 fixed upon the shaft 17 upon which is a double clutch, illustrated in Fig. 4. As this form of clutch is repeated in this machine a single illustration and description will suffice for all. 18 is a collar rigidly fixed upon the shaft 17. At each side of the collar 18 is a friction-wheel 19, loose upon the shaft 17. The flanges of these friction-wheels overlap and are adapted to frictionally engage the flanges 20 of the friction-members 21 rigidly secured to the shaft 17. Interposed between the inner ends of the hubs 19^a of the wheels 19 and the collar 18 are pairs of sleeves or collars 22, the meeting faces of which are wedge-like or cam-shaped, as clearly indicated in Fig. 4. The inner member of each pair 22 abuts against the collar 18, the outer members abutting against the inner ends of the hubs 19^a. The outer cam-shaped members are provided with arms 23 the extremities of which are secured to the deck of the machine or to some other stationary part in such manner that they may be slightly moved transversely. The inner cam-members are provided with arms 24 extending upwardly, each of these arms being provided with a rod 25 leading to a lever, not shown, within convenient reach of the operator. It will be seen that the movement of either of the arms 24 will, by the wedge-like action of the meeting cam-surfaces of the parts 22, cause a slight movement of the friction-wheels 19 along the shaft 17. When either of the friction-wheels 19 is projected into contact with its companion friction-wheel 21 by the movement of the rod 25, the reverse movement of this rod permits the frictional contact to be broken by means of the thrust of stout springs 26 interposed between the two friction-wheels. Fixed rigidly upon each of the hubs 19^a is a gear-wheel 27 in

mesh with gear-wheels 28, the former being capable of slight transverse movement upon the latter when the clutch mechanism just described is actuated. The shaft of the gears-wheels 28 carries a pair of beveled pinions 29 engaged with opposite sides of a beveled gear 30 the vertical shaft of which, 31, carries at its lower end a pinion 32 in mesh with the teeth of the circular rack 5. It will now be seen that when the appropriate pair of friction members 19-20 are thrown into contact the pinion 32 will, through the shaft 31 and the gears 29-30, be caused to traverse the circular peripheral path of the rack 5, thus causing the body of the machine to swing upon the center 6 in either direction as may be desired.

Referring next to the part of the apparatus designed to raise and lower and govern the height of the shovel 12: A cable 33 connected in the usual or any preferred manner with the shovel is threaded around pulleys 34 at the shovel and 35 at the tip of the boom and leads to and around drum 36. This drum is loose upon shaft 37, journaled on frame B, which shaft is driven by gear 38, in mesh with the gear 16. The drum 36 carries a friction-member 39 similar to the wheel 19 (Fig. 4) and which co-acts with a companion friction-member 40, 95 similar to the wheel 20-21, (Fig. 2) which is fixed upon the shaft 37.

Loose upon the shaft 37 are collars 37^a like the collars 22, Fig. 4, and which serve to actuate the clutch members 39-40 in 100 a manner which will now be understood without further explanation. This clutch-mechanism is the same as that already described except that it requires no reversing mechanism and no disengaging springs like 105 the springs 26, for the reason that power is applied only in the lifting operation, the reverse movement being obtained by the weight attached to the cable 33. It will be understood without illustration that the 110 collars 37^a are controlled by arms like the arms 23-24, one of the arms being suitably connected with a controlling lever within convenient reach of the operator. The gear 38 being in motion and the clutch members 115 39-40 being engaged, the cable 33 is wound upon the drum lifting the shovel to the described height. As the shovel is lifted the body of the machine is swung to the right or left as may be desired through the swinging mechanism hereinbefore described. The releasing of the clutch 39-40 permits the shovel to fall to its point of attack.

Coming now to the devices for projecting and retracting the dipper-arm 11, it will be 125 understood that the operation of a mechanism for thrusting and withdrawing a dipper-arm mounted upon a vertically adjustable boom by means of a remote engine, instead of by means of an engine mounted directly upon 130

the boom, presents considerable mechanical difficulties. These I overcome by means of the devices now to be described: The heel of the boom is pivoted upon horizontal shaft 41 journaled on frame B which arrangement permits the vertical adjustment of the tip of the boom through the rods 42 and turnbuckles 43 suitably connected with and braced upon the frame of the body of the machine. 44 is a gear on shaft 45 journaled on frame B and in mesh with the gear 38. The shaft 45 is provided with a double clutch mechanism constructed and operated the same as that illustrated in Fig. 4, and as hereinbefore described, the same reference numerals being employed for the clutch on the shaft 45 as that on the shaft 17. Upon the shaft 41 are gear-wheels 46 in mesh with the gear-wheels 27 on shaft 45. The gear-wheels 46 are rigidly connected with beveled gears 47 as shown in Fig. 3, the gears 46 and 47 being loose on the shaft 41. 48 is a shaft journaled on the boom and extending centrally and longitudinally thereof. At its lower end the shaft 48 is provided with a beveled gear-wheel 49 in mesh with both the beveled-gears 47. At its upper end the shaft 48 is provided with a beveled gear 50 in mesh with a like gear 51 on shaft 52 journaled across the boom about midway of its length and carrying at its outer ends pinions 53. (See Fig. 2.) These pinions are in mesh with gears 54 mounted on the extremities of shaft 55 journaled across the boom. The boom is composed as usual of two parallel members, usually metal plates, between which the dipper handle is mounted and moves. Upon the shaft 55 are pinions 56 which mesh with racks 57 secured to the underside of the dipper-handle 11.

Upon the engagement of the appropriate clutch-members 19-20 upon the shaft 45, the corresponding gear 27 will, through gears 46, 47, 49, shaft 48, gears 51, 53, 54, 56 and rack 57,—in the order named,—cause the forward thrust or retreat of the dipper handle 11 as may be desired.

It will now be seen that by means of a single non-reversing engine or motor and the proper operation of the various clutch mechanisms herein described, all of the usual steps requisite in the excavating of earth may be readily and conveniently performed. It will also be understood that notwithstanding the necessity for extreme changes in the pitch of the boom,—as in digging deep trenches or on work where the dump is extremely high,—and regardless of any yielding or springing of the boom or settling of the machine, the devices for projecting and retracting the dipper-arm remain uniformly efficient, due to the fact that the power is delivered to the dipper-arm through gears mounted upon the body of the machine and in constant alignment with and concentric with the hinge of the boom.

Having described my invention, what I claim and desire to secure by Letters Patent, is—

1. In an excavating machine of the described character, a truck, a body rotatably mounted upon the truck, a boom transversely rigid upon the body but pivotally mounted upon the body, a horizontal shaft 75 which forms such pivot, a dipper-arm mounted upon the boom, a shovel carried by the dipper-arm, mechanisms for rotating the body upon the truck, mechanisms, including gears co-axial with the boom-pivot, for projecting and retracting said dipper-arm, mechanisms for vertically swinging said shovel, an engine mounted on said body, and devices for at will throwing either or any or all of said mechanisms into or out of operative relation with said engine.

2. In an excavating machine of the described character, a truck, a body rotatably mounted upon the truck, gears for rotating the body, a vertically adjustable boom pivoted upon a pivot-shaft horizontally mounted at the front end of the body, a dipper-handle operatively mounted upon the boom and having secured thereto a toothed rack, a shovel carried by the dipper-handle, gears for projecting and retracting the dipper-handle, said gears comprising gear-wheels on said pivot shaft, a shaft journaled in and in parallel relation with the boom, and gears on said latter shaft 100 adapted for operative connection with the gears on the pivot-shaft and with said rack, combined with an engine adapted to run continuously in one direction, and clutch-mechanisms adapted to reversibly throw 105 said gears into and out of operative relation with said engine.

3. In an excavating machine of the described character, a rotatable body, a boom pivoted at its heel upon said body, a horizontal shaft which forms such pivot, means for the vertical adjustment of the point of said boom upon said pivot shaft, a dipper-arm reciprocable on said boom, gears on said boom for actuating the dipper-arm, gears 110 on said pivot-shaft, operative connections between said two gears, an engine, driving connections between the engine and the gears on said pivot-shaft, and means for throwing said latter gears into and out of operative 115 relation with said driving connections.

4. In an excavating machine of the described character, a rotatable platform, a shaft horizontally mounted at the forward part of said platform, a boom pivoted for 125 vertical movement but horizontally rigid upon said shaft, a pair of beveled gears upon said shaft, means for driving either of said beveled gears independently of the other, a shaft journaled longitudinally of said boom, 130

a beveled gear carried by said shaft at its inner end and in engagement with said pair of beveled gears, a dipper-arm reciprocably mounted upon said boom, and driving connections between the outer end of said latter shaft and said dipper arm.

5. In an excavating machine, a boom, a dipper-handle, a rack on the handle, gears mounted on the boom and operatively engaged with the rack, a shaft horizontally mounted and upon which the heel of the boom is pivoted, gears on said shaft, and driving connections intermediate and operatively connected with said two gears combined with a non-reversing engine and connections between the engine and said gears on the pivot-shaft for driving such gears in either direction.

6. In an excavating machine, a horizontally rotatable body, an engine mounted at one end of said body, a boom having its heel pivoted at the other end of said body, a horizontally mounted shaft forming such pivot, means for the vertical adjustment of the boom upon said pivot, a dipper-arm, a shovel carried by said arm, gears upon the boom for reciprocating the dipper-arm, gears upon said pivot-shaft, operative connections between said two gears, a train of gears between the engine and the gears on said pivot-shaft, and means operable by said train for hoisting said shovel and for rotating said body.

7. In an excavating machine, a horizontally rotatable body, an engine mounted at one end of said body, a boom having its heel pivoted at the other end of said body,

a horizontal shaft forming such pivot, means for the vertical adjustment of the boom upon said pivot, a dipper-arm, a shovel carried by said arm, gears upon the boom for reciprocating the dipper-arm, gears upon said pivot-shaft, operative connections between said two gears, a train of gears between the engine and the gears on said pivot-shaft, means operable by said train for hoisting said shovel, and means for rotating said body, combined with reversible clutch-mechanisms for connecting with and disconnecting from said train the said two gears and said hoisting and said rotating means.

8. An excavating machine of the described character, comprising a truck, a horizontally revoluble body upon the truck, a non-reversing motor at one end of the body, a boom at the other end of the body, a dipper-arm and shovel carried by the boom, gears for rotating the body, gears for projecting and retracting the dipper-arm, a drum and tackle for raising and lowering the shovel, gears for actuating said drum, said several gears being in train with the engine, and for each of said gears a reversing clutch-mechanism, said gears for projecting and retracting the dipper-arm including a fixed horizontal shaft upon which the heel of the boom is hinged.

In testimony whereof I affix my signature in presence of two witnesses.

HARRY J. BARNHART.
